UNITED STATES PATENT OFFICE.

JOHN MERRY, OF ELDORADO COUNTY, CALIFORNIA.

MODE OF MARKING STOCK.

Specification of Letters Patent No. 29,619, dated August 14, 1860.

To all whom it may concern:

Be it known that I, JOHN MERRY, of the county of Eldorado and State of California, have invented a new and Improved Mode of 5 Branding Stock; and I do declare that the following is a full and exact description of the same.

The nature of my invention consists in providing a self-advertising brand for stock 10 by stamping upon suitably shaped buttons the name and location of the owner and fastening them upon the horn and ear by means of a lock herein described.

To enable others skilled in the art to use 15 my invention I will proceed to describe its construction and application.

I construct of any suitable metal, buttons of the shape of Figures 1 and 2 and stamp upon their circular faces the name and location 20 of the owner as shown in the accompanying drawing. Fig. 3 is a sectional drawing of Fig. 1.

A and B are two circular flanges screwing into each other in the manner shown. 25 Through the center of the flange A I drill the hole C leaving a shoulder near the bottom. The small hole penetrating into B contains a thread.

Fig. 4 is a screw having a right handed thread corresponding to the thread in B and 30 a left-handed thread corresponding to the thread in the key Fig. 5 separated by a narrow flange. The brand is locked by turning the screw into its key firmly by means of a wrench and meeting it in the hole C and 35 turning until the screw is left in the brand. The same lock is applied to Fig. 2, of which Fig. 6 is a sectional drawing. The ear brand is applied by cutting a hole through the ear and inserting the flange B. A is then 40 screwed on and the lock applied. The horn brand is applied by screwing it upon the horn and inserting the lock so as to intercept the thread.

What I claim as my invention and desire 45 to secure by Letters Patent is—

The application of the owner's name and address by stamping or otherwise and the mode of locking or securing the brand.

JOHN MERRY.
